(57) **CLAIM**

The ornamental design for a housing end for lighting fixture, substantially as shown and described.

DESCRIPTION

FIG. 1 is a perspective view of a housing end assembly for a lighting fixture with tubular lens, showing our new design, according to the first embodiment;

FIG. 2 is a front elevation view thereof, according to the first embodiment;

FIG. 3 is a rear elevation view thereof, according to the first embodiment;

FIG. 4 is a right side elevation view thereof, according to the first embodiment;

FIG. 5 is a left side elevation view thereof, according to the first embodiment;

FIG. 6 is a top plan view thereof, according to the first embodiment; and

FIG. 7 is a bottom plan view thereof, according to the first embodiment;

FIG. 8 is a perspective view of a housing end for a lighting fixture with tubular lens according to a second embodiment;

FIG. 9 is a front elevation view thereof, according to the second embodiment;

FIG. 10 is a rear elevation view thereof, according to the second embodiment;

FIG. 11 is a right side elevation view thereof, according to the second embodiment;

FIG. 12 is a left side elevation view thereof, according to the second embodiment;

FIG. 13 is a top plan view thereof, according to the second embodiment; and,

FIG. 14 is a bottom plan view thereof, according to the second embodiment.

The broken lines shown in the drawings illustrate unclaimed environmental structure and form no part of the claimed design.
